ttf quick brown
fuzzy quick brown

1.3

Two stylized letters, 'H' and 'A', arranged side-by-side. The letters are composed of a dense grid of black dots, giving them a textured, halftone appearance. The 'H' is a standard capital letter 'H' with vertical strokes and a central crossbar. The 'A' is a standard capital letter 'A' with a vertical stem and a curved top bar.

Two stylized letters, 'R' and 'F', arranged side-by-side. The letters are composed of a dense grid of black dots, giving them a textured, halftone appearance. The 'R' is a standard capital letter 'R' with a vertical stem and a curved top loop. The 'F' is a standard capital letter 'F' with a vertical stem and a horizontal crossbar.

Two stylized letters, 'S' and 'G', arranged side-by-side. The letters are composed of a dense grid of black dots, giving them a textured, halftone appearance. The 'S' is a standard capital letter 'S' with a vertical stem and a large, sweeping curve. The 'G' is a standard capital letter 'G' with a vertical stem and a large, sweeping curve on the right side.
